DENTAL DRILL

Ralph Kestler, Corona, Long Island, N. Y.

Application November 1, 1941, Serial No. 417,441

2 Claims. (Cl. 32—40)

The present invention relates to an improvement in dental drills and more particularly to a device for guiding a drill.

The object of the present invention is to provide a device for drilling or cutting interior or exterior walls in the teeth of a patient so that all of said walls will be parallel to each other while the patient holds the device in his mouth.

Another object of the present invention is to provide a device which is inexpensive to manufacture, light in weight and durable in structure.

In using the drill without the assistance of the present invention the dentist encounters great difficulty in drilling parallel walls of separated teeth so that two or more crowns which support intermediate bridge work will fit properly, and most of the time the wall of one or both teeth will be undercut or out of line and necessitate a great deal of work to provide a perfect fit, but with the present invention, however, all of these difficulties are obviated, and a perfect fit is assured with the first drilling.

Other objects of the present invention will be brought out in the following specification.

Reference will be had to the accompanying drawing forming a part of this specification in which similar reference characters indicate corresponding parts throughout the several views, in which:

Fig. 1 is a top plan view of one embodiment of the present invention.

Fig. 2 is a front elevation of Fig. 1.

Fig. 3 is a detail in vertical section of the drill holder.

Fig. 4 is a small perspective showing in a general way the device in use, and

Fig. 5 is a diagrammatic view showing the parallel cut lines on two separated teeth.

Referring to the drawing wherein I have shown, by way of illustration merely, a device for guiding a dental drill comprising a plastic compound mouth pad 10, supporting a bracket 11, which is integral with a cup 12. The cup 12 encloses a ball 13 which is held rigidly by a lock nut 14 to rigidly hold a pin 15 in various angular positions.

Slidably mounted upon the pin 15 is a sleeve 16, which has an integral arm 17 projecting at right angles therefrom and said arm is provided with an enlarged portion 18 which fits into a bifurcated portion 19 on a link 20.

The link 20 also has a similar enlarged portion 21 fitting into a bifurcated portion 22 on a pin 23, and both of these joints 18 and 21 have ball bearings 24 which are held in place by set screws 24' to permit of easy motion. The pin 23 carries

a drill holder 25 which has a split sleeve 26 clamped around the pin 23 by a clamp 27.

The drill holder sleeve 26 is integral with a nut 28 (see Fig. 2) for receiving a pin 29 on the 5 drill holder proper 30.

The drill holder proper 30 is normally held against a seat 31 in the bottom of the nut 28 by reason of a spring 32 the function of which will be hereinafter described.

10 A spring housing 33 is screwed to the reduced portion 34 of the nut 28, and to keep the spring 32 and pin 29 in proper position I have provided a set screw 35 secured to the upper end of the pin 29. The drill 36 is securely clamped to the holder 30 by the clamp 37 which is similar in every respect to the clamp 27.

In operating the device the dentist first heats the mouth pad 10, which is a plastic compound and easily softened, and then inserts the pad into the patient's mouth as shown in Fig. 4. The patient must bite down on this pad 10 to hold the device while the dentist does the cutting. After the patient bites down on the pad 10, the nut 14 on the ball joint is loosened and the pin 15 is placed at the proper angular position relative to the vertical axis of the tooth about to be cut. The nut 14 is then tightened and the device is ready to cut any number of teeth walls all parallel to each other.

25 Suppose in Figs. 4 and 5 the pin 15 is set corresponding to the vertical axis of the tooth A, the dentist will cut tooth A parallel to the vertical axis of the pin 15 since the sleeve 16 rides up and down on this pin 15 and carries all the arms 35 and linkage with it, the drill 36 will of course follow the same axial path as the sleeve 16, and when the drill 36 is moved over to tooth B the same path is followed as in tooth A.

30 Therefore, all the lines C—C in Fig. 5 will be cut parallel to each other as long as the patient holds the pad between his teeth. This allows of a nice fit for crown bridge work or interior connections and can be accomplished with great ease and celerity, thereby insuring a perfect fit 45 in the first instance.

35 It will of course be understood that the showing here is merely illustrative and many modifications and niceties of adjustment can be made without departing from the principle of the present invention.

40 I claim:

45 1. A device of the kind described comprising a plastic compound pad adapted to be held in the mouth of a patient, a ball joint carrying an adjustable vertical pin, a sleeve riding on said

pin, an integral arm connected to said sleeve, a link connected to said arm, a drill holder carrying a drill connected to the other end of said link, and means comprising said sleeve for guiding said drill for cutting adjacent teeth walls parallel to each other.

2. A device for cutting or drilling all parallel walls inside or outside of adjacent teeth, comprising a plastic compound mouth pad adapted to be held between the upper and lower teeth of a patient, an arm rigidly secured to said mouth pad, a ball socket rigidly secured to said

5 arm, an angular adjustable pin having a ball on the lower end thereof seated in said ball socket, means for tightening said ball, a sleeve movably mounted on said pin, an arm integral with said sleeve, a linkage movably connected to said arm, a drill holder adapted to receive a drill secured to said linkage, means in said drill holder to permit of free movement of said drill in a horizontal plane, and means comprising said sleeve riding up and down on said pin for guiding said drill in the same path as said sleeve.

RALPH KESTLER.
